THERMOSTATIC CONTROL FOR ELECTRIC HEATERS

Frank Reingruber, Albany Ave., Bartlett, N.H.

Filed June 18, 1963, Ser. No. 75,404

Term of patent 14 years

(Cl. D52—7)

Fig. 1.

Fig. 2.

Fig. 3.

Fig. 4.

Fig. 5.

Fig. 6.

FIG. 1 is a front elevation of a thermostatic control for electric heaters embodying my new design.

FIG. 2 is a view of the right hand side of the same.

FIG. 3 is a top plan view of the same.

FIG. 4 is a view of the back of the control.

FIG. 5 is a view of the left hand side of the control.

FIG. 6 is a bottom plan view of the control.

I claim:

The ornamental design for a thermostatic control for electric heaters, substantially as shown.
